(57) **CLAIM**

The ornamental design for a video game peripheral detection device, as shown and described.

DESCRIPTION

FIG. 1 is a perspective view of a video game peripheral detection device in accordance with our design;

FIG. 2 is a top view of the video game peripheral detection device of FIG. 1;

FIG. 3 is a right side view of the video game peripheral detection device of FIG. 1;

FIG. 4 is a left side view of the video game peripheral detection device of FIG. 1;

FIG. 5 is a front view of the video game peripheral detection device of FIG. 1;

FIG. 6 is a rear view of the video game peripheral detection device of FIG. 1;

FIG. 7 is a bottom view of the video game peripheral detection device of FIG. 1;

FIG. 8 is a perspective view of an alternate embodiment of a video game peripheral detection device in accordance with our new design;

FIG. 9 is a top view of the video game peripheral detection device of FIG. 8;

FIG. 10 is a right side view of the video game peripheral detection device of FIG. 8;

FIG. 11 is a left side view of the video game peripheral detection device of FIG. 8;

FIG. 12 is a front view of the video game peripheral detection device of FIG. 8;

FIG. 13 is a rear view of the video game peripheral detection device of FIG. 8; and,

FIG. 14 is a bottom view of the video game peripheral detection device of FIG. 8.

The broken lines indicate environment of the structure and form no part of the claimed design.
